UNITED STATES PATENT OFFICE

JULIUS BING, OF EISENACH, GERMANY, ASSIGNOR TO THE FIRM MAGNET-WERK
G. M. B. H., EISENACH SPEZIALFABRIK FÜR ELEKTROMAGNET-APPARATE, OF
EISENACH, THURINGIA, GERMANY

MACHINE FOR DISINTEGRATING WASTE WOOD

Application filed January 11, 1929, Serial No. 331,927, and in Germany January 17, 1928.

The fibrous wood-material adapted to form the pulpy raw-material used in the manufacture of cellulose, paper and cardboard has heretofore been made by grinding of the wood which in the form of trunk-wood being cut into fixed lengths was kept for this purpose in contact with a grindstone. The said method requires a disproportionately large amount of work, due to the fact that the wood is converted in a single working step from the long-tailed timber form into the ground material. Moreover according to the said known method the working up of waste wood of irregular form is not possible.

According to my invention an extremely high reduction of the mechanical work is attained by previously disintegrating the wood into coarse pieces by splitting, breaking, cutting or shearing, before it is converted into the final raw-material adapted to form a pulp. The amount of mechanical work which is necessary for the said working operations is extremely smaller than the amount of mechanical work which is necessary for the grinding. Moreover the improved method according to the invention involves the great advantage that all wood left as wastes in other industrial branches may be worked up to a valuable fibrous wood material, this working effect being not possible with the known preparatory working machines.

According to my invention the previous disintegration is executed in a machine similar to crushing mills. The said machine substantially comprises a casing which is provided on the inside with slanting ribs, preferably formed with cutting edges and a rotary body being arranged in said casing and being also provided with longitudinal ribs which may form cutting-edges. The said rotary body is tapering off towards the inlet at first in a very acute angle and then in an angle forming a steep incline with the axis of the rotary body. The ribs of the rotary body are adapted to cooperate with the ribs of the casing to effect the disintegration of the wood, it being essential that at least one of the ribs or another element being adapted for this purpose protrudes beyond that part

of the rotary body which is highly tapered towards the axis of rotation.

This device is adapted to convert the waste wood of irregular form into an even intermediate product. The said even product is then further disintegrated in a second device which may be incorporated into a unitary construction together with the first device. The said second device may be of shorter axial length than the first device, and the disintegrating elements of said second device are of finer conformation than those of the first device. After having passed the second device the goods may be ground in the known manner to be converted into the final raw-material adapted to form a pulp so far as the said final product has not yet been reached by the preceding working operations.

In the drawings two preferred embodiments of apparatus for carrying out the process according to my invention are illustrated.

Fig. 1 is a vertical axial section of a machine with a vertical axis of rotation.

Fig. 2 is a horizontal section according to the line II—II of Fig. 1.

Fig. 3 is a side-elevation and a partial section in a plane at right angles to that of Fig. 1.

Fig. 4 is a vertical axial section of a device with a horizontal axis of rotation.

Figs. 5 to 8 illustrate in a larger scale special disintegrating elements of the secondary disintegrating zone.

For the nature of the invention it is of no importance whether the shaft of the machine is vertically arranged, as shown in Figs. 1 to 3 or horizontally arranged, as shown in Fig. 4.

The disintegrating machine according to the Figs. 1 to 3 comprises two main parts: The casing 1 which is illustrated in the form of an upright hollow cylinder and a rotary body 3 which is arranged in said cylinder and splined on a vertical shaft 2. The shaft 2 is mounted with its lower end in a foot step bearing 4 which is arranged in an opening 6 through the frame 7 carrying the said casing and which is supported by the said

frame through the intermediary of arms 5 forming a spider.

On its upper end the shaft 2 is mounted in a spider 8 bridging the upper open end of the casing 1 which is provided on the inside with slanting or helical abutment ledges or ribs 9. These ribs, the inner edges of which may be knife-like, preferably are not directly arranged on the casing but as represented on special inserted pieces in the form of hollow cylindrical sections. In this way abutment ribs which have become blunt or otherwise damaged may easily be substituted. But the ribs may also be integral with the casing. In both cases the material is preferably cast steel.

The rotary body has the form of a bell, the outer shell of which is a frustum of a cone tapering slightly towards above. The basis of said cone is a circle falling rather closely into the cylinder form corresponding with the inner surfaces of the ribs 9. Thus between the rotary body 3 and the casing 1 or the ribs 9 of the latter an annular cavity is formed the radial breadth of which is gradually increased from bottom to top, and the upper part of the said annular cavity is rather abruptly enlarged to a considerable extent.

30 The rotary body 3 is provided with ribs 10, and according to the illustrated embodiment eight ribs are equally distributed over the periphery. The ribs 10 may be integral with the rotary body to form with it a single piece 35 of cast steel. According to the illustrated embodiment, however, such ribs are arranged on special inserted pieces 10b which are in the form of hollow frustums of cones being connected with the rotary body 3 in such a way that they may easily be substituted.

The radial dimensions of the ribs 10 are varying in such a way that up to about half the height of the casing 1 the outer surfaces of the ribs or the edges of said ribs being the 45 front edges with respect of the direction of rotation lie in the cylindrical surface which is given through the effective inner edges of the abutment ledges 9, whereas in the upper part the edges of the ribs are in some distance from the cylindrical surface on its inside. In the lower section the distance is only small, but in the upper section, at the transition of the acute-angled frustum of cone with the upper surface of the rotary 55 body, the distance is gradually more increased, and at the hub-portion 12 the ribs 10 go over into the rotary body 3.

In this way three different working zones are formed which are an upper zone 13 extending in the vertical direction approximately from the upper side of the rotary body 3 to the upper edge of the casing 1 and in the radial direction from the inside of the casing to the hub 12 or to the shaft 2 of 60 the rotary body 3 respectively, a second zone

14 forming an annular cavity gradually tapering like a cone substantially up to half the height of the casing, and a third zone 15 in which the ribs 10 of the rotary body are substantially adjacent the ribs 9 of the casing. Each of the three zones extends approximately along one third of the height of the casing 1.

At least one of the ribs of the rotary body 3 and according to Fig. 1 the rib 16 on the right hand is differing from the other ribs, as its working edge extends from bottom to top substantially in a cylindrical surface and its upper end is substantially adjacent the upper edge of the casing 1. In this way the 75 conveying surface within the zone 13 nearly fills up the cross-section of the latter.

On the upper end of the casing 1 there is a top piece 17 which forms a hopper for the supply of the material to be worked and which supports the spider 8 forming the bracket for the bearing of the shaft 2. Above the said bearing a jack or bracket 18 projects from the inside of the top piece 17 in a horizontal plane, and the said jack or bracket forms an abutment for a crusher which will be described afterwards. The edge 19 being the front edge of the abutment with respect of the direction of rotation of the body 3, which edge extends substantially in a radial direction, lies behind the edge 20 of that arm of the spider 8 which is nearest to the abutment.

The distance between the edge 19 and the edge 20 which is the rear edge of the said arm with respect of the direction of rotation corresponds approximately with the thickness of boards or other pieces of wood which have to be worked up. The said distance may be adjusted in accordance with the thickness of the wood to be worked by displacing the bracket 18 in a circumferential direction.

The lower part of the bell-shaped body 3 is connected with a wheel-body 22 by means of screws 21. A rim of gear wheel 24 is keyed to the peripheral part 23 of the said wheel-body. The said rim is in mesh with a bevel gear wheel 25 which is mounted on a driving shaft 26 being in connection with any source of energy which is not illustrated in the drawing.

A ring 28 of relatively small axial extension is at 27 adjacent the lower part of the bell-shaped body 3. On the outside this ring 28 is provided with ribs 29 which are preferably inclined relatively to the generatrix of the respective cylindrical surface and adapted to cooperate with abutment ledges or ribs 30 on the enclosing part 31 of the casing, said ribs being preferably also inclined and formed with knife edges. The abutment ribs 30 are shaped to correspond with the ribs 5 of the casing, but a greater number of ribs 30 and also of the ribs 29 are provided. The working edges of the ribs 29 are adjacent the 120 125 130

cylindrical surface formed by the cutting-edges of the abutment ledges 30. The part 31 preferably consists of a plurality of sectors adapted to be substituted.

5 The last mentioned device is adapted for a subsequent disintegration of the material into fine particles. The said device may also be independent of the device which serves for the previous disintegration. The device for

10 the subsequent disintegration may be adjusted for different sizes of grain. For this purpose the annular bodies or sectors which bear the disintegrating elements 29, 30 are detachably arranged so that they may be easily substituted by corresponding pieces which bear other disintegrating elements. The knife-like elements for the subsequent disintegration may be substituted by grinding or rasping elements.

20 In the Figs. 5 to 8 detachable sectors are illustrated which are provided with rasping teeth. The Figs. 7 and 8 show in an elevation and in a cross-section a fragment of a sector which may be used as a part of the annular body 31 according to Fig. 1. The Figs. 5 and 6 illustrate in corresponding views a fragment of a sector which is to be used in a device for the subsequent disintegration, said device forming part of a modified construction which will be described afterwards. In both cases the sector bodies are designated with 31a and 31b respectively, the rasping teeth with 30a and 30b respectively.

25 In a machine which serves both for the previous and the subsequent disintegration passages of larger cross-section become necessary on account of the fact that the volume of the material to be worked up is increased corresponding to the progression of the disintegration. The said passages of greater area are easily to be obtained by enlarging the diameters of the body or the bodies of revolution. Thereby also a higher peripheral velocity of the disintegrating elements is attained which is advantageous for the disintegration of the goods into fine particles.

30 A machine of a corresponding construction is illustrated in Fig. 4. Another possibility consists in employing a special drive for increasing the peripheral velocity of the cutting elements for the disintegration into fine particles, the said increase being relatively to the peripheral velocity of the cutting-edges of the rotary body 3. In this case the before mentioned cutting elements had to be independently rotatable.

35 As already stated the diameters of the working parts of the device for the previous disintegration are much larger than those of the machine described before. Moreover in the machine according to Fig. 4 the shaft 2a of the bell-shaped rotary body 3a is horizontally arranged and directly coupled with the driving shaft 26a.

The operation of the machine according to Figs. 1 to 3 is the following:

The irregular pieces of waste wood are brought into the hopper 17 of the casing 1. The smaller pieces immediately enter into the annular space 14 and are there disintegrated by cutting, splitting, shearing, breaking, squeezing and rasping through the cooperation of the ribs 16 of the rotary body 3 with the abutment ledges 9 of the casing. In this operation the goods are disintegrated to such an extent that they form a relatively uniform mass which gradually moves downwardly along the helical ledges 9 and is further disintegrated in the subsequently working device between the cutting elements 29, 30.

The larger pieces of wood remain at first in the zone 13 on the shoulder of the rotary body 3. The greater part is taken along by the rib 16 which projects upwardly, and the said rib presses the goods against the abutment ledges 9. In accordance with the shape and the quality of the piece of wood and its position between the respective abutment and the rib 16, the disintegrating effect is different.

A log of wood coming in its longitudinal direction into contact with an abutment is plainly sheared off. The parts into which the log had been disintegrated will then glide into the bevel cavity 14 and are there further disintegrated without difficulty. A log of wood coming endwise in contact with the rib 16 is split, and the subsequent working is the same as that described. In a corresponding way larger pieces of wood being in other positions are disintegrated in the upper part of the machine.

40 In every case the machine due to the arrangement of the rib 16 protruding upwardly into the space 13 reduces pieces which are most difficult to be worked, whereby clogging of the disintegrating device is avoided. The pieces into which the wood has been split or cut by the rib 16 are further disintegrated by breaking, squeezing or shearing to smaller pieces which enter into the annular space 14 which tapers downwardly so that the goods are further disintegrated.

45 Instead of a single rib as rib 16 protruding into the space 13 a plurality of the ribs 10 may be elongated to project upwardly. The number of the projecting ribs will correspond with the size of the apparatus.

50 Pieces of wood of relatively considerable length such as outside planks coming as waste material from the saw-mills are broken by means of the abutment 18. The respective pieces of wood are brought between the abutment 18 and the respective arm of the bearing-spider 8 into contact with the rotary body 3 (Figs. 1 and 2) so that the said pieces are taken by the upwardly projecting rib 16 and broken into pieces the length of

which corresponds with the distance of the lower edge of the spider from the rotary body. The broken pieces are then taken along by the ribs of the rotary body and fed to the place of the normal disintegrating action.

The upper abutment 18 avoids a tilting of an inserted piece of wood under the influence of the pressure which is exerted on its lower end by the rib 16. After the breaking off of the lower end the piece of wood glides further downwardly for a certain distance under the influence of its own weight or through the pushing action exerted by the labourers. In consequence thereof the end of the piece of wood which projects through the abutment formed by the spider 8 is again taken by the rib 16 and broken off. With the said arrangement special auxiliary machines for previously working waste wood of irregular shape are rendered unnecessary.

The operation of the machine illustrated in Fig. 4 substantially corresponds with the operation described above with exception of such differences which depend upon the horizontal arrangement of the shaft 2. Here the waste wood is thrown into the hopper 17a. The feed of the material to the zone of the subsequent disintegration is not effected by gravity but principally by centrifugal action.

The device for subsequently disintegrating the material is differing from the corresponding device described before inasmuch as the cooperating disintegrating elements are arranged in planes or faces being substantially at right angles to the axis of the rotation. The discharge end of the zone of the subsequent disintegration is formed by an annular cavity which is enclosed with a certain distance by the respective part of the casing 1a. The material leaving the zone of the subsequent disintegration is centrifuged towards the said part of the casing. The material finally drops out of the casing through a lower opening 6a.

The improved method described does not only apply on the manufacture of a fibrous wood material which is a raw material necessary for many technical purposes but also on the economical utilization of all wastes of the industrial branches of the wood working industry. Heretofore such wastes had to be burnt up, and even the burning up was combined with difficulties on account of the irregularity of the material, of the expensive preparatory work to render the material adapted for being burnt in furnaces to which the material is manually fed, of the bad utilization of the grate-area and of the small calorific intensity. The advantages of the improved method of working up waste wood of irregular shape for a refinement of the wood to fibrous wood material are the following:

(1) The manufacture of a fibrous wood

material by a simple working up of waste wood.

(2) The production of a valuable raw material for the manufacture of artificial stone and artificial wood.

For the burning up of waste wood the advantages are the following:

(1) An improved utilization of the calorific intensity of the fuel and also a better utilization of the grate-area and correspondingly a considerable economy in the consumption of the fuel and an increase of the calorific effect of a steam-plant.

(2) A considerable reduction of the conveying costs on account of the possibility of automatically charging and automatically conveying the disintegrated material.

(3) A considerable diminution of the danger of fire in the plants through continually removing the wastes.

(4) A great utilization of the available room.

(5) Cleanliness and clear arrangement in the plant.

I claim:

1. In a disintegrating machine for wood, a cylindrical casing having slanting ribs on its inside, a rotatable shaft within said casing, a rotary body having a hub portion on one end which is fast to said shaft, said body having straight ribs adapted to cooperate with the ribs of said casing for disintegrating the wood, said body being of such a bell-shape that its surface near the feeding end of the casing extends steeply declined with respect to said casing from the hub portion towards the casing and then slightly declined with respect to the casing along the walls of the same so as to form two different working zones which are a first zone adjacent the inlet of the casing, said zone being of great radial dimension and extending substantially from the casing to the hub portion of the shaft, and a second zone of much smaller radial dimension, said second zone having the form of an annular cavity tapering towards the discharge end.

2. In a disintegrating machine for wood, a cylindrical casing having slanting ribs on its inside, a rotatable shaft within said casing, a rotary body having a hub portion on one end which is fast to said shaft, said body having straight ribs adapted to cooperate with the ribs of said casing for disintegrating the wood, said body being of such a bell-shape that its surface near the feeding end of the casing extends steeply declined with respect to said casing from the hub portion towards the casing and then slightly declined with respect to the casing along the walls of the same so as to form two different working zones which are a first zone adjacent the inlet of the casing, said zone being of great radial dimension and extending substantially from the casing to the hub portion of the shaft.

shaft, and a second zone of much smaller radial dimension said second zone having the form of an annular cavity tapering towards the discharge end, part of the ribs attached to said rotary body extending further into said first working zone than the remaining ribs.

3. In a disintegrating machine for wood, a cylindrical casing having slanting ribs on its inside, a rotatable shaft within said casing, a rotary body having a hub portion on one end which is fast to said shaft, said body having straight ribs adapted to cooperate with the ribs of said casing for disintegrating the wood, said body being of such a bell-shape that its surface near the feeding end of the casing extends steeply declined with respect to said casing from the hub portion towards the casing and then slightly declined with respect to the casing along the walls of the same so as to form two different working zones which are a first zone adjacent the inlet of the casing, said zone being of great radial dimension and extending substantially from the casing to the hub portion of the shaft, and a second zone of much smaller radial dimension, said second zone having the form of an annular cavity tapering towards the discharge end.

4. In a disintegrating machine for wood, a casing, a rotary member within said casing, means attached to said member and casing for disintegrating wood, said casing carrying a plurality of abutments, and means on said rotatable member adapted to coat with said abutments for breaking endwise fed pieces of wood such as planks and the like.

5. In a disintegrating machine for wood, a casing, a rotary member within said casing, means attached to said member and casing for disintegrating wood, a feed hopper having a plurality of abutments, and means on said rotatable member adapted to coat with said abutments for breaking endwise fed pieces of wood such as planks and the like.

6. In a disintegrating machine for wood, a casing, a rotary member within said casing, means associated with the outer side of said rotary member and means associated with the inner side of said casing for disintegrating the wood, said means being in one part of the working zone in much closer proximity to each other than in another part, the distance of said means from each other increasing towards the supply opening of the machine, and means on said casing adapted to coat with said means on said rotary member for breaking endwise fed pieces of wood.

7. In a disintegrating machine for wood, a

cylindrical casing having slanting ribs on its inside, a rotatable shaft within said casing, a rotary body having a hub portion on one end which is fast to said shaft, said body having straight ribs substantially uninterrupted from one end of said rotary body to the other end and being adapted to cooperate with the ribs of said casing for disintegrating the wood, said body being of such a bell-shape that its surface near the feeding end of the casing extends steeply declined with respect to said casing from the hub portion towards the casing and then slightly declined with respect to the casing along the walls of the same so as to form two different working zones which are a first zone adjacent the inlet of the casing, said zone being of great radial dimension and extending substantially from the casing to the hub portion of the shaft, and a second zone of much smaller radial dimension, said second zone having the form of an annular cavity tapering towards the discharge end.

8. In a disintegrating machine for wood, a cylindrical casing having slanting ribs on its inside, a rotatable shaft within said casing, a rotary body having a hub portion on one end which is fast to said shaft, said body having straight ribs substantially uninterrupted from one end of said rotary body to the other end and being adapted to cooperate with the ribs of said casing for disintegrating the wood, said body being of such a bell-shape that its surface near the feeding end of the casing extends steeply declined with respect to said casing from the hub portion towards the casing and then slightly declined with respect to the casing along the walls of the same so as to form two different working zones which are a first zone adjacent the inlet of the casing, said zone being of great radial dimension and extending substantially from the casing to the hub portion of the shaft, and a second zone of much smaller radial dimension, said second zone having the form of an annular cavity tapering towards the discharge end.

9. In a disintegrating machine for wood, a casing having a feeding part for the wood, a shaft rotatable within said casing, a bell-shaped rotary body on said shaft, slanting ribs on the inside of said casing, ribs on the outside of said rotary body adapted to cooperate with said slanting ribs for disintegrating the wood, two stationary abutments adjacent the feeding part of said casing, and spaced apart from each other in axial direction, and an upwardly projecting abutment on said rotary body, said inner and outer abutments being so positioned as to hold a board to be disintegrated in the path of said upward projecting abutment.

10. In a disintegrating machine for wood,

a casing having a feeding part for the wood; a shaft rotatable within said casing, a bell-shaped rotary body on said shaft, slanting ribs on the inside of said casing, ribs on the 5 outside of said rotary body adapted to co-operate with said slanting ribs for disintegrating the wood, two stationary abutments adjacent the feeding part of said casing, and spaced apart from each other in axial direction, the inner one of said abutments being to a certain distance displaced in the direction of rotation of said body with respect to the outer abutment, and an upwardly projecting abutment on said rotary body, said inner and 15 outer abutments being so positioned as to hold a board to be disintegrated in the path of said upward projecting abutment.

In testimony whereof I affix my signature.

JULIUS BING.
